(57) **CLAIM**

The ornamental design for a bluetooth (wireless) notifier, as shown and described.

DESCRIPTION

FIG. 1 is a front, right side, perspective view of a bluetooth (wireless) notifier showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, right side, perspective view thereof mounted on the necklace-type accessories; and,

FIG. 9 is a front, right side, perspective view thereof mounted on the watch-type accessories.

The broken lines indicate unclaimed portion of the article that form no part of the claimed design.

1 Claim, 4 Drawing Sheets
